INTAKE MANIFOLD FOR INTERNAL-COMBUSTION ENGINES

Application filed February 23, 1927. Serial No. 170,115.

My present invention relates to an improvement in intake manifolds for internal combustion engines. The particular object of the invention is to provide a simple device by which the distribution of fuel to the several intake ports of an internal combustion engine, which ports are supplied through a single manifold passage, will be more uniform than heretofore. As is well-known to those skilled in the art, the problem of distribution, by which is meant the supplying of equal amounts of fuel under uniform conditions to each of the inlet ports of an internal combustion engine, is one of the most difficult problems connected with the design of multi-cylinder internal combustion engines for automobiles and the like. This problem is of particular importance in connection with six and eight cylinder engines having cylinders formed in a single block and the failure to accomplish uniform distribution is one of the chief causes of difficulty with engines of this type. For instance, trouble is frequently experienced with the end cylinder of an eight cylinder engine of the kind referred to owing to the fact that there is a tendency with the heavy particles of fuel to travel in a straight line and thus reach the cylinder furthest away causing fouling of that cylinder and the spark plug and imperfect combustion therein. If passages are designed to correct this, the trouble may be corrected in the end cylinder but it is likely to be thereby transferred to one of the other cylinders. These difficulties are particularly pronounced in "low velocity" manifolds of relatively large capacity and substantially rectangular cross-section with flat floors, such as have been found especially suitable for high speed engines in order to obtain good breathing, since the velocity of the gases is insufficient to prevent the accumulation of unvaporized fuel on the floor of the passage.

My present invention results in practically uniform distribution to all of the cylinders under all conditions and is accomplished by a relatively small change in the construction of the intake manifold which supplies the branches leading to the several valve ports.

When there are unvaporized particles of

heavy fuel in the mixture delivered by the carburetor these particles are thrown by centrifugal force to the outer wall of the curved passage and, in the case of a low velocity manifold, tend to accumulate, by gravity, on the floor or bottom wall and not mix with the air stream. As the several valve ports suck or breathe successively the stream of mixture is required to change direction suddenly passing first to one port and then to another. In so far as the mixture is a perfect gas or substantially so this presents no obstacle since the gas responds immediately to the suck of the successive cylinders. When, however, the fuel is unvaporized and is carried along either on the bottom or outer side of the manifold, it does not enter the air stream, and is not likely to become mixed with air, but eventually finds its way substantially unvaporized into one of the cylinders. My invention provides a deflector which extends part way across the passage inwardly from the outer wall of the manifold and upwardly from the floor thereof, being connected with the floor throughout its length, being of the full height of the passage where it joins the outer wall, but being of less height at its inner end, and having a curved upper free edge. This deflector terminates abruptly at about the middle of the passage, thereby forming a take-off so that the unvaporized fuel which creeps along the outer wall and bottom of the manifold passage is picked up and blown off into the middle of the air stream in a position such that it can travel with equal ease to any of the intake ports. Since the unvaporized fuel which is blown off the edge of the deflector is itself substantially in the middle of the air stream and since it can travel in a substantially straight line to whichever of the ports is breathing it does not again reach the side walls of the passages and, due to the increased velocity of the air stream at this point, is picked up from the floor and is carried directly to whichever cylinder the mixture is then being supplied to.

I find in practice that this simple device results in a very material improvement in distribution and that in a six cylinder engine

provided with it, no one cylinder shows more fouling than another thus indicating that the mixture supplied to each cylinder is substantially uniform.

Referring to the drawings:

Fig. 1 is a plan view of a portion of an internal combustion engine together with a portion of an external manifold to supply the mixture thereto.

Fig. 2 is a side elevation of the parts shown in Fig. 1.

Figs. 3, 4, 5 and 6 are sections of the manifold taken on lines 3-3, 4-4, 5-5 and 6-6, respectively of Fig. 1.

Fig. 7 is a perspective view showing the deflector, the upper part of the manifold passage being broken away.

Figs. 8, 9 and 10 are diagrams showing the action of the manifold as the successive cylinders breathe.

In the drawings, at A is shown a cylinder block, at B, C and D three of the inlet valves, at E, F and G branch passages leading to the inlet valves and at H an external manifold supplying all three cylinders. It will be understood that I do not limit myself to the number of cylinders shown and further that the other end of the engine may be of the same construction, what is shown being sufficient to illustrate the invention. The intake manifold H as shown is of the low velocity type, having a passage of relatively large, substantially rectangular cross section and a flat floor is curved in the horizontal plane as shown in Fig. 1, so that any unvaporized particles of the liquid fuel tend to be thrown by centrifugal force against the outer wall *h* and having contacted with the outer wall tend to cling to the wall and, due to the relatively low velocity of the air stream, to gravitate to the floor. Unless in some way diverted these particles will pass along the floor of the passage G to the end valve D. With a layout of valves and passages like that shown in the drawings, the end cylinders of the engine are likely to receive an undue proportion of the heavy part of the fuel which will be indicated by fouling of the combustion space, piston head and spark plug.

In accordance with my invention, I form in the manifold passage H a deflector *e*, the shape of which will be clearly seen in Figs. 1, 3, 4, 5, 6 and 7. This deflector joins the floor of the passage throughout its length and bends inwardly from the wall *h*, i. e. is curved in plan as shown in Fig. 1. At the point where the deflector joins the wall *h* it is the full height of the wall, but decreases in height as it bends inwardly to form a free upper edge which is curved to overhang slightly as shown in Figs. 5 and 6. The deflector terminates at about the median line of the intake passage, and at the tip the deflector has a height about $\frac{1}{3}$ the total height of the pas-

sage. The tip of the deflector is at a point midway of the air stream leading to each of the valves.

The operation of my device is as follows: When the particles of heavy gas which are unmixed with the air in the manifold H emerge from the carburetor, they tend to travel in a straight line and consequently are thrown against the outer curved wall *h*. The particles are held against this wall by centrifugal force and by surface tension and are dragged along by the action of the air current, tending however, due to the low velocity of the latter, to gravitate to the floor. When such of them as still adhere to the outer wall reach the deflector they are carried inwardly and downwardly, while those which travel along the floor are intercepted and directed toward the tip of the deflector. The overhanging portion of the deflector prevents the particles being thrown over the upper edge and insures that all of them are carried toward the center of the air stream. The shape of the deflector, which I call for convenience a propeller-shape, is important as it insures the delivery of all the heavy particles in to the air stream. When the particles of unvaporized fuel reach the vertical edge *f* of the deflector *e* they are blown off into the air stream. If the valve B is breathing the action will be as shown in Fig. 8, the general direction of the air stream being shown by the light arrows, while the direction of the heavy particles of fuel are shown by the darker arrows. It will therefore be seen that while the cylinder B is breathing the heavy particles of fuel are drawn into that cylinder. When cylinder C is breathing the action will be as shown in Fig. 9. In that case also the particles are thrown off the tip of the deflector and being in the middle of the air stream are thus carried directly to the valve C. They have no opportunity to contact with the walls and therefore there is little or no danger of fouling. When the end cylinder is breathing the action indicated in Fig. 10 occurs. In this case it will also be seen that the particles are blown off the edge of the deflector into the middle of the air stream and thus are carried directly to the end valve D. By this arrangement the heavy fuel which comes to the edge of the deflector is carried into whichever cylinder is breathing, and therefore the heavy fuel which formerly tended to find its way entirely to one cylinder is now distributed equally among all the cylinders.

In practice I find it convenient to make the vertical edge of the deflector substantially in a line with the plane of the side wall of the cylinder block since in this way, the deflector can be made wholly in the manifold casting, but it will be understood that the parts may be otherwise constructed.

What I claim is:

1. A low velocity intake manifold for in-

ternal combustion engines having a passage provided with a deflector extending part way only thereacross from one wall to substantially the middle of the passage, said deflector being joined with the floor of the passage throughout its length, and having adjacent its inner end an overhanging free upper edge.

2. A low velocity intake manifold for internal combustion engines having a passage provided with a deflector extending part way only thereacross from one wall to substantially the middle of the passage, said deflector being joined with the floor of the passage throughout its length, being of the full height of the passage where it adjoins said wall, but being of less height adjacent its inner end and curved to form an overhanging free upper edge.

3. A low velocity intake manifold for internal combustion engines having a curved passage provided with a deflector extending part way only thereacross from its outer wall to substantially the middle of the passage, said deflector being joined with the floor of the passage throughout its length, and having adjacent its inner end an overhanging free upper edge.

4. A low velocity intake manifold for internal combustion engines having a passage with a flat floor and provided with a deflector extending part way only thereacross from one wall to substantially the middle of the passage, said deflector being joined with the floor of the passage throughout its length, and having adjacent its inner end an overhanging free upper edge.

In testimony whereof I affix my signature.
STEPHEN I. FEKETE.
